United States Patent Office.

JOHN S. PEMBERTON, OF ATLANTA, GEORGIA.

Design No. 3,521, dated June 1, 1869.

DESIGN FOR A TRADE-MARK.

The Schedule referred to in these Letters Patent and making part of the same.

To all whom it may concern:

Be it known that I, JOHN S. PEMBERTON, of Atlanta, in the county of Fulton, and State of Georgia, have invented a new and improved Design for Trade-Mark; and I do hereby declare that the following is a full, clear, and exact description thereof, which will enable others skilled in the art to make and use the same.

This invention relates to a new and original design for a trade-mark for the sale of our "Globe-Flower Sirup;" and consists of a branch or sprig of the "globe flower," embracing three leaves and blossoms combined.

The two lower leaves *a a'* spread to the right and left from the stem, while the other and larger leaf *b* stands nearly upright, with the flower *c* directly above the stem *d*, which points downward.

Above the left-hand leaf is the word "globe" in Roman capitals. To the left of the point of the central leaf is the word "of." To the right, and extending from near the upper point of the central leaf to near the point of the right-hand leaf *a'*, is the word "flower" in capitals.

The above words "globe-flower" incline downwards from left to right.

Centrally, over the whole, on a line curving upward, are the words "compound sirup" in capitals.

The leaves are their natural color, or green. The blossom is its natural color, or yellow.

The words "globe-flower" are in red color, the word "of" is blue, and the words "compound sirup" are blue, shaded with red, the whole being on a white ground.

Having thus described my invention,

I claim as new, and desire to secure by Letters Patent—

The above-described design for a trade-mark, substantially as and for the purpose set forth.

The above specification of my invention, signed by me, this   day of   , 1869.

JOHN S. PEMBERTON.
